FREQUENCY MODULATION DETECTOR
CIRCUITMurray G. Crosby, Riverhead, N. Y., assignor to
Radio Corporation of America, a corporation
of Delaware

Application July 10, 1942, Serial No. 450,355

4 Claims. (Cl. 250—27)

My present invention relates to frequency modulation receivers, and more particularly to an improved method of, and means for, reducing the effects of amplitude modulation introduced by virtue of round-topped resonance curve characteristics of signal selector circuits.

In the past it has been proposed to eliminate the amplitude modulation limiter stage from receivers of frequency modulated carrier wave energy (FM). When the limiter is removed from such a receiving system, say one of the universally-used superheterodyne type, one of the effects encountered is the introduction of amplitude modulation due to the variations of frequency engendered by virtue of the round-topped selectivity curve of the intermediate frequency (I. F.) amplifier which precedes the usual discriminator-rectifier network. Such amplitude modulation shows up as a distortion in the receiver output. Aside from the use of a limiter stage to remove amplitude modulation, various inverse modulation circuits have been proposed and described in my application Serial No. 416,443, filed October 25, 1941, and in my application Serial No. 435,467, filed March 20, 1942.

It may be stated that it is one of the main objects of my present invention to provide a receiver of angular velocity modulated carrier wave energy wherein the effect of amplitude modulation is minimized by adjusting the discriminator characteristic so that compensating distortion is introduced which cancels the undesired amplitude modulation (AM).

Another important object of this invention is to provide a discriminator circuit for a frequency modulation receiver, wherein a compensating distortion is applied to the discriminator characteristic so that the resulting overall discriminator characteristic is linear.

Another object of the invention is to reduce the effects of amplitude modulation, introduced by a round-topped I. F. selectivity characteristic, in a frequency modulation receiver of the type which does not employ a limiter stage per se.

Still other objects of the invention are to improve generally the simplicity and efficiency of FM receivers, and more especially to provide FM receivers of the superheterodyne type, free of any limiter stage per se, which are reliable in operation and are economically manufactured and assembled.

The novel features which I believe to be characteristic of my invention are set forth with particularity in the appended claims; the invention itself, however, as to both its organization

and method of operation will best be understood by reference to the following description taken in connection with the drawings in which I have indicated diagrammatically a circuit organization whereby my invention may be carried into effect.

In the drawings:

Fig. 1 shows a circuit arrangement of a discriminator-rectifier network of an FM receiver embodying the invention.

10 Figs. 2a to 2f inclusive show various characteristics of the invention.

Referring now to Fig. 1, there is shown here that portion of an FM receiver of the superheterodyne type located between an early I. F. 15 amplifier and the modulation voltage utilization network. Assuming that the receiver is operated in the presently assigned FM band of 42-50 megacycles (mc.), those skilled in the art are fully acquainted with the fact that in this band each 20 FM channel has a permissible deviation width of 200 kilocycles (kc.). Actually, at the transmitter the carrier frequency is deviated over a range of 150 kc. It is sufficient for the purposes of this application to point out that at the transmitter the carrier frequency is deviated back and 25 forth with respect to a center or mean frequency (F_c) in accordance with modulation signal amplitude. The rate of frequency deviation depends upon the modulation frequencies per se. The 30 generic expression "angular velocity-modulated carrier wave energy" is to be understood as covering either frequency modulated, or phase modulated, carrier wave energy.

In the FM receiver the radiated energy is amplified at ultra-high frequency in one or more amplification stages which have been adjusted to the center frequency of the particular desired FM channel. The amplified FM energy is then reduced in center frequency to the I. F. value.

35 The latter may be chosen from a range of 2 to 20 mc.; by way of illustration it can be assumed that the I. F. value is of the order of 4.3 mc. Of course, the frequency reduction of the center frequency to I. F. value does not affect the deviation range of the FM energy. Hence, both prior 40 to the converter and after the converter the selector circuits have a pass band width of the order of 200 kc., or at least in excess of the overall deviation range of the FM energy.

45 Considering Fig. 1 specifically, therefore, let it be assumed that numeral 1 designates an I. F. amplifier which feeds the discriminator network of the FM detection circuit. The I. F. amplifier may be of usual construction. Its signal grid 1' 50 is to be understood as being connected to a prior

I. F. amplifier stage (or, if desired, to the I. F. output circuit of the converter stage). The I. F.-tuned transformer T couples the prior amplifier to tube 1. The plate 14 of tube 1 is connected to a point of proper positive potential through series-arranged coils 2 and 3. Coil 2 is shunted by tuning condenser 2', while coil 3 is shunted by tuning condenser 3'. Each of coils 2 and 3 is, moreover, shunted by a respective damping resistor 12 and 13. The cathode circuit of amplifier tube 1 includes the usual bypassed bias resistor 1''.

The circuits 2-2' and 3-3' provide the usual discriminator network for transforming the FM energy into AM energy. Those skilled in the art are fully acquainted with the functioning and structure of the discriminator network. Circuit 2-2' is tuned to a frequency spaced from the center frequency by a predetermined frequency amount. Circuit 3-3' is tuned to a frequency spaced from the center frequency by the same frequency amount, but on the other side of center or mean frequency. It is desired that the frequency spacings between the resonant peaks of the two discriminator circuits exceed the overall deviation range of the center frequency. Of course, the latter value would be the operating I. F. value in the present instance.

It will be noted that no limiter stage per se is employed between the I. F. amplifier and the discriminator circuits. Those skilled in the art are fully aware of the function of a limiter network. It acts to eliminate amplitude modulation effects which may develop on the carrier. Such amplitude modulation effects are created by fading, extraneous noise, and because of the round-topped selectivity curve of the various selector circuits prior to the discriminator network. In my aforementioned applications, I have shown various circuits for eliminating AM effects on the FM energy without using a limiter per se. It is desirable to utilize a simple method of eliminating such AM effects, so that the detected output voltage will be a function solely of the frequency deviation of the carrier and not produce harmonic distortion by virtue of the carrier amplitude variation.

The discriminator functions to convert the frequency-variable, constant-amplitude carrier energy into carrier energy whose amplitude is variable in accordance with the modulation, but whose center frequency remains invariable. The discriminator output energy is subjected to rectification in the manner shown in Fig. 1. For example, a pair of rectifier diodes 4 and 5 have their cathodes arranged in series with the load resistors 8 and 9. The anode 4' is connected by coupling condenser 20 to the plate side of discriminator circuit 2-2'. The junction of resistors 8 and 9 is connected to the junction of a pair of resistors 6 and 7 arranged in series between anodes 4' and 5'. The junction of resistors 6 and 7 is connected by coupling condenser 21 to the junction of coils 2 and 3. The anode end of resistor 7 is grounded.

Each of resistors 8 and 9 is shunted by an I. F. bypass condenser, and these bypass condensers are respectively designated by the numerals 8' and 9'. The modulation signal voltage corresponding to the FM component of the received waves is taken off from the anode end of resistor 6. The detected FM voltage is derived from the rectified voltages developed across each of resistors 6 and 7; these rectified voltages are in polarity opposition relative to the grounded end of re-

sistor 7. Detected AM signal voltage may be taken off from the cathode end of resistor 8. The detected AM voltage is derived from the rectified voltages developed across resistors 8 and 7; these rectified voltages are in additive phase relative to the grounded end of resistor 7.

In explaining the functioning of the present invention, attention is first directed to the typical round-topped I. F. selectivity characteristic shown in Fig. 2a. This is assumed to be the selectivity curve of the I. F. amplifier up to tube 1. It is possible to obtain a more ideal flat-topped characteristic, but usually the expense goes up as this is done. Furthermore, such a more ideal characteristic is difficult to align, and is liable to drift. The actual discriminator characteristic of Fig. 2b is that proposed by my present invention. It will be noted that the characteristic is straight, or linear, in the middle portion where the I. F. characteristic is relatively flat. In other words, the middle linear portion of the curve of Fig. 2b corresponds to the relatively flat portion of the characteristic of Fig. 2a. In the portions of the characteristic of Fig. 2a where drooping commences, the discriminator characteristic rises a compensating amount so that the overall characteristic is linear as shown in Fig. 2c.

I have found that a discriminator characteristic such as is shown in Fig. 2b may be produced with the circuit shown in Fig. 1. As stated heretofore, the discriminator is composed of off-tuned circuits 2-2' and 3-3'. These discriminator circuits are off-tuned to either side of the center frequency, so that their individual resonance curve characteristics are as shown, for example, by the curves A and B of Fig. 2d. When the discriminator network is properly adjusted, an overall effective linear discriminator characteristic may be obtained as shown in Fig. 2c. This may be done by adjusting the inductive coupling between coils 2 and 3 to be equal to the capacitive coupling between the off-tuned circuits. The reference character M denotes the inductive coupling, while the dotted capacity C denotes the capacitive coupling between the discriminator circuits.

In addition, the damping resistors 12 and 13 are adjusted properly to apportion the selectivity of the discriminator circuits. It is pointed out that the linear discriminator characteristic of Fig. 2c would be desirable if a limiter stage were used prior to the discriminator network. A simple way to provide the characteristic of Fig. 2b is as follows: Choose M, C, 12 and 13 to get the curve of Fig. 2c, and then raise the values of 12 and 13 to produce the curve of Fig. 2b. For this adjustment the damping resistors 12 and 13 are made higher in resistance, so that the tuned circuits are more sharply selective. The result is the characteristic of 2b, which has the desired compensating distortion.

The compensating distortion of the discriminator characteristic is equally effective on amplitude modulation reception with the same detecting system. Assume, now, that AM carrier waves are being received by the same receiver, and that the latter has been adjusted to receive such waves. In this case the detected outputs are added, instead of subtracted, so that a double-peaked characteristic is secured, as shown in Fig. 2e. This curve is taken at the upper end of resistor 8 assuming omission of the round-topped curve of Fig. 2a. Increasing the value of the damping resistors has the effect of making this double-peaked characteristic more marked. The overall

result of the round-topped I. F. characteristic of Fig. 2a and the double-peaked characteristic of Fig. 2e is the flat-topped characteristic shown in Fig. 2f. It is assumed, in this case, that the I. F. amplifier feeding the detector has the characteristic of Fig. 2a. Detected AM voltage, taken off from the cathode end of resistor 8, may be amplified in the usual way. The networks 10 and 11 show resistor-condenser filter networks used respectively in the FM and AM take-off leads to remove carrier energy from the output circuits.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:

1. In combination, in a receiver of angular velocity-modulated carrier waves, a detector provided with a discriminator network, a selective amplifier coupled to said discriminator to apply amplified modulated waves to the latter, said amplifier being tuned to a predetermined reference frequency and having a frequency vs. amplitude characteristic which possesses substantially drooping flanks relative to said reference frequency whereby amplitude modulation effects are introduced on said carrier waves, said discriminator being tuned to a center frequency equal to said reference frequency and being constructed and arranged to have a frequency vs. direct current output characteristic whose slope is relatively linear over the median region thereof but rises in opposite directions from the median region a sufficient amount substantially to compensate for the said drooping flanks thereby to compensate for said amplitude modulation effects.

2. In combination, in a receiver of frequency modulated carrier waves, a detector comprising a pair of rectifiers, a frequency discriminator network, a selective amplifier coupled to said discriminator network to apply amplified frequency modulated waves to the latter, said amplifier being tuned to a predetermined frequency and having a frequency vs. amplitude characteristic which possesses substantially drooping flanks whereby amplitude modulation effects are introduced on said carrier waves, said discriminator network being tuned to a frequency equal to said predetermined frequency and being constructed and arranged to have a frequency vs. direct current output characteristic whose slope is rela-

tively linear over a predetermined central region thereof but rises in opposite directions from said central region a sufficient amount substantially to compensate for the said drooping flanks thereby to compensate for said amplitude modulation effects, and means connecting said rectifiers in polarity opposition to produce a modulation signal voltage corresponding to the frequency modulation of said carrier waves.

3. In combination, in a receiver of frequency modulated carrier waves, a detector provided with a frequency discriminator network, a selective amplifier coupled to said discriminator to apply frequency modulated waves to the latter, said amplifier being tuned to a predetermined operating frequency and having a frequency vs. amplitude characteristic which possesses a substantially round top and substantially drooping flanks, whereby amplitude modulation effects are introduced on said carrier waves, said discriminator network comprising a pair of resonant circuits tuned to respective frequencies located on opposite sides of said operating frequency, said pair of resonant circuits being magnetically and capacitatively coupled to provide a frequency vs. direct current output discriminator characteristic whose slope is relatively linear over the median region thereof but rises in opposite directions from the median region a sufficient amount substantially to compensate for the said drooping flanks thereby to compensate for said amplitude modulation effects.

4. In combination, in a receiver of frequency modulated carrier waves, a detector provided with a frequency discriminator network, a frequency selective circuit coupled to said discriminator network to apply frequency modulated waves to the latter, said selective circuit being tuned to a predetermined reference frequency and having a frequency vs. output amplitude characteristic which possesses substantially drooping flanks relative to said reference frequency whereby amplitude modulation effects are introduced on said carrier waves, said discriminator network being tuned to a center frequency equal to said reference frequency and being constructed and arranged to have a frequency vs. direct current output characteristic whose slope is relatively linear over the median region thereof but rises in opposite directions from the median region a sufficient amount substantially to compensate for the said drooping flanks thereby to compensate for said amplitude modulation effects.

MURRAY G. CROSBY.
